C. CASSIDY

SPOON

Filed March 5, 1923

FIG. 2

BY

INVENTOR
C. Cassidy
J. Ledermann
ATTORNEY

UNITED STATES PATENT OFFICE.

CHAUNCEY CASSIDY, OF GREAT FALLS, MONTANA.

DESIGN FOR A SPOON.

Application filed March 5, 1928. Serial No. 25,664. Term of patent 14 years.

To all whom it may concern:

Be it known that I, CHAUNCEY CASSIDY, a citizen of the United States, residing in Great Falls, in the county of Cascade, in the State of Montana, have invented a new, original, and ornamental Design for a Spoon, of which the following is a specification, reference being had to the accompanying drawing, forming a part thereof.

I claim:

The ornamental design for a spoon as shown.

CHAUNCEY CASSIDY.
